UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

MEANS FOR STOPPING PULSATIONS IN CENTRIFUGAL COMPRESSORS.

1,188,995.

Specification of Letters Patent. Patented June 27, 1916.

Application filed August 14, 1913. Serial No. 784,713.

To all whom it may concern:

Be it known that I, RICHARD H. RICE, a citizen of the United States, residing at Lynn, county of Essex, State of Massachusetts, have invented certain new and useful Improvements in Means for Stopping Pulsations in Centrifugal Compressors, of which the following is a specification.

Centrifugal compressors as commonly constructed comprise one or more stages, each stage having an impeller with suitably shaped vanes, a means which receives fluid from the impeller and converts the principal portion of its velocity into pressure, and an inclosing casing. The impeller or impellers are driven by electric motors, steam turbines, or other prime movers. In some cases the compressor is driven at constant speed, the driving element being controlled by a speed governor or equivalent device. In other cases the compressor is driven at variable speed to cause a constant volume of fluid to be delivered. These compressors usually discharge into a receptacle having considerable volumetric capacity over and above that of the compressor itself. Such a receptacle may be the pipe line to which the compressor is connected, blast furnaces or other apparatus connected thereto. Such compressors operate on what is termed a rising characteristic at light loads, meaning thereby that an increase in the volumetric output is accompanied by an increase in pressure. This peculiarity is wholly or at least in a large part due to the action of the means for converting velocity into pressure, said means receiving and acting on the fluid from the impeller before it enters the pipe line or other apparatus connected thereto. The use of said means, while having a very important function in the production of compressed fluid gives rise, under light load conditions, to what is commonly known as pulsation or surging of the fluid undergoing compression. The load at which pulsation begins varies with different compressors, but as a general proposition it may be stated to be from between 60% to 40% of full load. The point at which pulsation begins is generally known as the "breakdown" point. The intensity of these pulsations varies with different compressors, with different capacities in the pipe line and apparatus supplied thereby, and frequently with changes in climatic conditions. In all cases they are

highly objectionable as will be readily appreciated.

My invention has for its object to overcome these highly objectionable surges or pulsations in compressors of the types referred to herein, and to that end I provide a valve on the inlet side of the compressor for throttling the admission. This valve should preferably be wide open from full load down to the "breakdown" point, after which it must throttle the passage through the conduit by an amount sufficient to prevent pulsation. This requires that the throttling increase as the volume admitted to the compressor decreases.

I have discovered that in order to prevent pulsations the throttling required from the "breakdown" point to no load is not a straight line function of the amount of fluid which the compressor is taking; i.e., of the load, but that it is of such a nature that the throttling must increase more rapidly than the change in load.

More specifically, therefore, the object of my invention is to provide an improved apparatus which will give the desired characteristic movements to the throttling valve. This apparatus is in addition to the governing mechanism which regulates the speed of the motor or prime mover employed to drive the compressor.

In the accompanying drawing which illustrates one of the embodiments of my invention, Figure 1 is a vertical section showing my improved mechanism; Fig. 2 is a partial vertical section taken at right angles to that of Fig. 1; Fig. 3 is a side elevation showing a weight for adjusting the action of the mechanism, and Fig. 4 is an end elevation of a centrifugal compressor showing the mechanism in position.

9 indicates the casing of the compressor having an inlet conduit 10 and a discharge conduit 11. Located within the casing is a bladed impeller 12 and stationary discharge vanes 13 which surround the impeller and act as means to convert velocity of the fluid received from the impeller into pressure. Between the vanes are passages that first converge and then diverge or they may be wholly divergent; this will depend upon the conditions of operation as to pressure. Air or other elastic fluid is delivered to opposite sides of the impeller by chambers which communicate with the supply

pipe 14. The impeller is mounted on a shaft 15 which is provided with suitable bearings and is driven by an electric motor or prime mover. Secured to the inlet conduit is a 5 downwardly turned elbow, the lower end of which is secured to an enlargement in the supply pipe.

The enlargement comprises two conical members 17 and 18 whose enlarged ends are 10 secured together by bolts. Mounted in the upper cylindrical portion of the conical member 17 is a butterfly valve or damper 19 which is mounted on a spindle 20. The spindle is provided with bearings carried 15 by the member 17. One end of the spindle extends through the casing and is turned at right angles to form a lever 21. Located on the under side of the valve and either formed integrally therewith or riveted thereto is a 20 lug 22 in which is a number of holes 23 suitably spaced apart. To the lug 22 is pivotally attached a rod 24. The lower end of the rod is held in position and guided by the spider 25 which is either cast integral 25 with the conical member 18 or attached thereto. Threaded on the rod 24 is a volume measurer made in the form of a floating disk 26 that is acted upon by the flowing fluid. That is to say, the float is raised 30 or lowered by changes in the volume of fluid entering the compressor, which float in turn opens or closes the valve 19 thereby throttling the fluid by an amount depending upon the position of the float. The amount 35 of this throttling is relatively greater at light loads than at heavy and should be sufficient especially at light loads to prevent pulsations by slightly modifying the characteristic of the compressor; *i. e.*, changing 40 it from a rising to an approximately horizontal one. The arrangement is preferably such that the throttle valve is held fully open for all loads above the "breakdown" point of the compressor. The floating disk 45 which is threaded on the rod is held in position by the lock nut 27. The lug 22 extends radially with respect to the center of the valve 19 and the holes 23 therein permit of relative adjustment of the valve and 50 floating disk 26. That is to say, by changing the point of connection of the rod 24 and valve a given movement of the float will cause the valve to open to a greater or less extent. Riveted or otherwise secured to the 55 butterfly valve is a weight 30 which may be composed of a number of thin metal strips, said weight serving to counterbalance wholly or in part the weight of the rod 24 and float 26. By increasing or decreasing 60 the number of plates or changing their position the effect of the weight on the flow measurer can be changed. Mounted on the lever portion 21 of the valve spindle is an adjustable weight 31 by means of which 65 the action of the parts can be changed or

regulated. By making the parts 17 and 18 conical as shown, the volume measurer will be extremely sensitive to variations in the volume of fluid flowing into the compressor. By providing the upper member with an 70 internal flange and the lower one with an external flange the two can readily be bolted together.

The motor which drives the compressor may be of any suitable type, and may be 75 provided with any desired form of governing mechanism for controlling its speed and also that of the impeller.

Assuming the weight 31 is set for any predetermined operating condition, the fluid 80 as it flows into the compressor acts on the under side of the volume measurer or float 26 and raises the same by a greater or less amount. This causes the throttle valve 19 to assume a position corresponding to the 85 amount of fluid flowing.

The connection between the float and the valve is preferably so adjusted that for all flows above the "breakdown" point the valve is wide open. If now the flow decreases to 90 the "breakdown" point then the float will lower a little, thus throttling the inlet to the desired degree. If the flow decreases still more, then the float will further close the valve. As already pointed out, however, this additional amount of throttling necessary to prevent pulsation at the lighter load must be greater in proportion to the load change as the load decreases. By using 95 an upwardly opening cone as 18, and arranging the volume measurer as shown, I reduce or avoid the throttling action which would otherwise take place at heavy loads. That is to say, as the measurer moves upward it occupies a position in the cone of 100 larger diameter, and hence a greater space is provided for the fluid between it and the surrounding wall of the conduit. In other words the relation of the volume measurer 105 26 with respect to the enlarged lower end 110 of the conical part 17 is such that at full volumetric flow the said measurer occupies a position where it will not throttle the passage of fluid flowing through the compressor. Looking at the matter another way, 115 the volume measurer under these conditions is above the throttling zone. When the measurer is thus positioned the throttle valve is wide open and hence permits free flow of the fluid undergoing compression.

By my improved structure wherein the valve and the float are formed separately and connected together, each can be made to obey a separate law in its movements, and I can thus obtain any desired characteristic 120 for the throttling of the valve.

In accordance with the provisions of the patent statutes, I have described the principle of operation of my invention, together with the apparatus which I now consider 125

to represent the best embodiment thereof; but I desire to have it understood that the apparatus shown is only illustrative, and that the invention can be carried out by 5 other means.

What I claim as new and desire to secure by Letters Patent of the United States, is:—

1. In an apparatus of the character described, the combination of a compressor 10 having an inlet, a valve therein for throttling the flow at light loads to prevent pulsations, a volume measurer in the conduit which is separate and distinct from the valve, and means for connecting the volume measurer to the valve, whereby the volume measurer may follow a different law in its movements from that which the valve follows.
2. The combination with a centrifugal 20 compressor having an inlet and an outlet, of means for stopping pulsations at light loads comprising a float whose position is changed by changes in volume of the fluid passing through the compressor, a valve which acts 25 to throttle the passage of fluid through the compressor, and means connecting the float to the valve for communicating movements of the float to the valve.
3. A centrifugal compressor having an inlet and an outlet, in combination with a float located in said inlet which is moved in 30 response to changes in volume of the fluid entering the compressor, a throttle valve located between the float and impeller of the compressor, and means connecting the float to the valve, said means being arranged to impart relatively different amounts of movement from the float to the valve varying in 35 accordance with the load.
4. The combination with a centrifugal 40 compressor having an inlet and an outlet, of means for stopping pulsations at light loads comprising a device responsive to and moving in accordance with variations in the 45 volume of fluid passing through the compressor, a valve which is separate and distinct from said device for throttling the fluid flowing through the compressor, means connecting the device to the valve whereby 50 the device may follow a different law in its movements from that which the valve follows, and a counterbalancing weight on the valve.
5. A centrifugal compressor having an 55 inlet and an outlet, in combination with a volume measurer, a valve for throttling the fluid flowing through the compressor, means connecting the volume measurer to the valve whereby the volume measurer may follow 60 a different law in its movements from that which the valve follows, a spindle for the valve having an arm, and an adjustable weight mounted on the arm.
6. A centrifugal compressor having an 65 inlet and an outlet, a conical member in the

inlet, a volume measurer located in the member near its enlarged end, a throttle valve pivotally supported in the inlet on the compressor side of the measurer, and a connection extending from the measurer to the 70 valve for opening the latter as the measurer moves outward from the enlarged end of the conical member.

7. A centrifugal compressor having an inlet and an outlet, a conical member in the 75 inlet, a volume measurer located in the member near its enlarged end, a throttle valve pivotally supported in the inlet on the compressor side of the measurer, a rod which connects the measurer and the valve, and a 80 spider which engages the rod and acts as a guide for it and the measurer.

8. A centrifugal compressor having an inlet and an outlet conduit, in combination with a volume measurer in one of the conduits, a means located in one of the conduits for throttling the fluid flowing through the compressor at light loads, means connecting the volume measurer to the valve whereby the volume measurer may follow a different 85 law in its movements from that which the valve follows, and means formed in one of the conduits and cooperating with the measurer to permit full volumetric flow of the fluid around the measurer at heavier 90 loads.

9. A centrifugal compressor having an inlet and an outlet, in combination with a volume measurer, a valve for throttling the fluid flowing through the compressor at 100 light loads, means connecting the volume measurer to the valve whereby the movements imparted to the valve by the volume measurer may bear any desired relation to the movements of the measurer, and an enlarged portion formed in the inlet and into 105 which the measurer is moved by the fluid at heavier loads to prevent the same from throttling the flow.

10. In combination, a conduit having a 110 frusto-conical section and a converging section, a float in the frusto-conical section, a valve located beyond the converging section, and a connecting means between the valve and float whereby the valve will be 115 moved by the float as the latter moves from a smaller to a larger part of said frusto-conical section.

11. In combination, a conduit having a 120 diverging section and a converging section, a float located in the diverging section, a butterfly valve located beyond the converging section, a rod pivotally attached to the valve and having said float adjustably mounted thereon, said valve being moved by 125 the float as it changes its position with changes in flow of fluid in the conduit.

12. In combination, a conduit having a 130 diverging and a converging section, a float located in the diverging section, a butterfly

valve pivotally supported in the conduit beyond the converging section, a rod that is pivotally attached to the valve at one end and carries said float between its ends, and
5 a guide for the rod in which it is free to move longitudinally in response to movements of the float.

In witness whereof, I have hereunto set my hand this 12th day of August, 1913.

RICHARD H. RICE.
